UNITED STATES PATENT OFFICE.

ISIDORE KRANZ, OF NEW YORK, N. Y.

DESIGN FOR AN ELECTRIC-LIGHTING FIXTURE.

Application filed February 20, 1926. Serial No. 16,605. Term of patent 3½ years.

To all whom it may concern:

Be it known that ISIDORE KRANZ, a citizen of the United States, and resident of New York city, in the county of New York and State of New York, has invented a new, original, and ornamental Design for Electric-Lighting Fixtures, of which the following is a specification, reference being had to the accompanying drawing, forming part thereof, in which the figure is a perspective

view of the electric lighting fixture embodying my design.

I claim:

The ornamental design for an electric lighting fixture, as shown.

Dated at New York, county of New York, State of New York, this 17th day of February, 1926.

ISIDORE KRANZ.
